Primary Examiner — Angela J Lee*(74) Attorney, Agent, or Firm* — Sughrue Mion, PLLC(57) **CLAIM**

I claim the ornamental design for a USB (universal serial bus), as shown and described.

DESCRIPTION

FIG. 1 is a front perspective view of USB (universal serial bus) showing my new design;
FIG. 2 is a front view thereof;
FIG. 3 is a rear view thereof;
FIG. 4 is a left-side view thereof;
FIG. 5 is a right-side view thereof;
FIG. 6 is a top plan view thereof;
FIG. 7 is a bottom plan view thereof; and,
FIG. 8 is a rear perspective view showing the USB (universal serial bus) in an open position.
The broken lines are for environmental purposes only and form no part of the claimed design.
